W. D'ARCY.

MITER BOX.

APPLICATION FILED SEPT. 1, 1916.

1,332,713.

Patented Mar. 2, 1920.

UNITED STATES PATENT OFFICE.

WELLINGTON D'ARCY, OF JACKSON, MICHIGAN, ASSIGNOR OF ONE-HALF TO SOLON H. BENBOW, OF KALAMAZOO, MICHIGAN.

MITER-BOX.

1,332,713.

Specification of Letters Patent.

Patented Mar. 2, 1920.

Application filed September 1, 1916. Serial No. 118,026.

To all whom it may concern:

Be it known that I, WELLINGTON D'ARCY, a citizen of the United States, residing at the city and county of Jackson, State of Michigan, have invented certain new and useful Improvements in Miter-Boxes, of which the following is a specification.

This invention relates to improvements in miter boxes.

10 The main objects of this invention are:

First, to provide an improved miter box which may be quickly knocked down and compactly arranged for transportation, or quickly set up or assembled.

15 Second, to provide an improved miter box which may be mounted on a saw horse or other support, such support constituting the bed piece of the box.

Further objects, and objects relating to 20 structural details, will definitely appear from the detailed description to follow.

I accomplish the objects of my invention by the devices and means described in the following specification. The invention is 25 clearly defined and pointed out in the claims.

A structure which is a preferred embodiment of my invention is clearly illustrated in the accompanying drawing, forming a 30 part of this specification, in which:

Figure I is a detail perspective of a miter box embodying the features of my invention with parts shown by dotted lines in order to better illustrate their relation.

35 Fig. II is an inverted plan view of the saw guide bar of my improved miter box.

Fig. III is a detail longitudinal section on a line corresponding to line 3—3 of Figs. II and IV, showing the arrangement of the 40 stop pin and the saw guide posts on the bar.

Fig. IV is a detail transverse section on a line corresponding to line 4—4 of Figs. II and III, showing the arrangement of the saw guide posts and means for detachably 45 securing them.

Fig. V is an enlarged detail section on a line corresponding to line 5—5 of Fig. II, showing the mounting of the saw guide bar upon its pivot.

50 Fig. VI is an enlarged detail perspective of one of the saw guide posts, showing its mounting upon the saw guide bar.

Fig. VII is a plan view showing means for detachably securing the cross piece to 55 the saw guide posts.

Fig. VIII is an enlarged detail vertical section on a line corresponding to line 8—8 of Fig. I, showing details of the back member supports.

Fig. IX is an enlarged detail section on a 60 line corresponding to the line 9—9 of Fig. II.

In the drawing similar reference characters refer to similar parts throughout the several views, and the sectional views are 65 taken looking in the direction of the little arrows at the ends of the section lines.

Referring to the drawing, the base 1 is provided with a quadrant 2 at the front thereof and has a number of vertically projecting spaced back supports at the rear side thereof. The base is lighted by forming holes therein. The back supports 3 have vertical grooves 5 in their rear sides adapted to receive the support members 6 of the 70 detachable back members 7. These support members 6 are in the form of spring straps arranged over the back members which are preferably formed of wood, the front ends of the straps being countersunk or seated in 75 grooves so that they are flush with the faces of the back members. The screws 8 are arranged through the arms of the supports and the back members as shown in Fig. VIII.

85 The miter box is provided with legs 9 so that it may rest on a bench or other support and is also adapted to be supported on a saw horse or other supporting bar 11, as illustrated in Fig. I. When so mounted on a saw 90 horse or other supporting bar the support member constitutes the bed piece of the miter box. The support member 11 is arranged on the base in front of the back member 7 and is clamped against the back 95 members and to the base by means of the clamping screw 10 arranged through an upwardly projecting lug 10' on the base, as shown in Fig. I. With the parts thus arranged the clamping screw not only serves 100 to secure the miter box to the support but also serves to clamp the back members rigidly in position.

On the under side of the base I mount a saw guide bar 12 by means of the pivot 13, the pivot being arranged through the base 1 as shown in Fig. V. The saw guide bar 12 is detachably secured to the pivot 13 by means of the locking slide or plate 15 slotted to engage the notches 14 in the pivot, the 110

notches being below the bar so that when the locking plate is moved longitudinally of the bar it is brought into and out of engagement therewith.

5 The slide or lock plate 15 is secured in its adjusted positions by means of the thumb screw 16 engaging the slot 16' in the lock plate. By this arrangement the saw guide bar can be readily removed and replaced as 10 occasion requires.

The saw guide posts 18 are arranged in holes or sockets formed in bosses 17 at the ends of the saw guide bar. These posts are supported in the sockets by means of the 15 pins 19 which engage notches 20 in the upper ends of the posts, the pins being extended to form finger pieces and constituting stop members coacting with the ends of the notches 20 to limit the rotative movement of the posts in their sockets.

20 The posts 18 are provided with notches 20' below the saw guide bar adapted to receive a spring catch 21 secured on the under side of the bar. The catches form retaining 25 means or locks preventing the withdrawal of the posts when adjusted to locked position. When the posts are rotated however to withdrawing position the locking springs are disengaged from the notches and the 30 posts may be drawn from their sockets. The ends of the posts are beveled at 22 on the sides of their notches 20' so that they may be engaged with the spring catches by merely pushing them into their sockets while 35 in locking position.

On their upper ends the rods are provided with cross bar engaging lugs 23 in the form of headed studs or extensions adapted to engage the slots 26 in the end pieces 25 of the 40 cross or top bar 27. The lugs 23 are so positioned on the posts that when the posts are in their unlocked position the lugs are aligned with the slots 26 thereby permitting the placing or removal of the cross bar, the 45 cross bar being locked when the posts are adjusted to locking position.

The saw guide rollers 28 are mounted on the posts for vertical rotative movement thereon. These rollers are provided with 50 rubber facings 29 and are held together by the cross pieces 31 which engage grooves in the upper ends thereof. The saw 30, which is shown conventionally, is adapted to slip between these guide rollers which move up 55 and down on the posts with the saw.

A spring clasp saw support 32 is mounted on the top piece 27 for supporting the saw in an elevated position. The saw guides normally rest on the supports 33 of the posts.

60 The saw guide bar is held in its adjusted position by means of the catch pin 35 which is supported by an arm 34 at the front of the quadrant 2, the quadrant being provided with a scale indicia and corresponding holes 65 36 for the pin.

With the parts thus arranged this improved miter box may be very quickly assembled and disassembled and when assembled may be compactly arranged for storage or transportation. It can be mounted upon 70 a saw horse which renders it of great convenience for use of carpenters and the like. The saw horse or support, as stated, constitutes the bed piece of the box.

I have illustrated and described my improvements in an embodiment which I find very satisfactory. I have not attempted to illustrate or describe various modifications in structural details which I contemplate as I believe the disclosure made will enable 80 those skilled in the art to which my invention relates to embody or adapt the same as conditions may require.

Having thus described my invention, what I claim as new and desire to secure by Letters Patent, is:

1. In a miter box, the combination of a base provided with upwardly projecting back supports having vertical grooves in their rear sides, back members disposed on 90 said base against said supports and provided with spring support members engaged in the said grooves, a clamping screw disposed horizontally opposite to said back supports, and a bar disposed on said base in front of 95 said back members and clamped thereon by means of said clamping screw, said bar constituting a bed piece and a support for the miter box.

2. In a miter box, the combination of a 100 base provided with back supports, back members disposed on said base against said supports, a clamping screw disposed horizontally opposite to said back supports, and a bed piece disposed on said base in front of 105 said back members and clamped thereon by means of said clamping screw, whereby said back members and bed piece are detachably secured to the base.

3. In a miter box, the combination of a 110 base provided with back supports, back members disposed on said base against said supports, and a clamping screw disposed horizontally opposite to said back supports and spaced therefrom whereby a bar may be 115 disposed between said back members and said clamping screw and clamped against said back members to hold them in position.

4. In a miter box, the combination of a base, removable back members, a bar disposed on said base, means for detachably securing said back members and bar to said base comprising a set screw adapted to engage said bar opposite said back members.

5. In a miter box, the combination of a 125 base, a saw guide bar pivoted on said base and provided at its ends with bosses notched at their upper ends and having saw guide post sockets therein, saw guide posts arranged in said sockets to be rotated therein, 130

- 5 said posts being provided with cross bar engaging lugs at their upper ends, pins on said posts constituting finger pieces and adapted to rest on the said bosses in engagement with 55
 5 said notches which constitute stops limiting the rotative movement of the posts, said posts being notched below said bar, the ends of the posts being beveled on their notched sides, spring post retainers mounted on said
 10 bar to engage said notches in said posts when the posts are adjusted to position, the beveled ends of the posts being adapted to engage said retainers when the posts are inserted, a cross bar having slots adapted to receive said
 15 lugs on said posts when the posts are turned to position to disengage said retaining members, and saw guides mounted on said posts.
6. In a miter box, the combination of a base, a saw guide bar pivoted on said base and provided at its ends with bosses notched at their upper ends having saw guide post sockets therein, saw guide posts arranged in said sockets to be rotated therein, pins on said posts constituting finger pieces and 70
 20 adapted to rest on the said bosses in engagement with said notches which constitute stops limiting the rotative movement of the posts, said posts being notched below said bar, the ends of the posts being beveled on
 25 their notched sides, spring post retainers mounted on said bar to engage said notches in said posts when the posts are adjusted to position, the beveled ends of the posts being adapted to engage said retainers when the 75
 30 posts are inserted, and saw guides mounted on said posts.
7. In a miter box, the combination of a base, a saw guide bar pivoted on said base and having saw guide post sockets therein, saw guide posts arranged in said sockets to be rotated therein, said posts being provided with cross bar engaging lugs at their upper ends, said posts being notched below said 80
 40 bar, spring post retainers mounted on said bar to engage said notches in said posts when the posts are adjusted to position, a cross bar having slots adapted to receive said lugs on said post when the posts are turned to one position, the lugs being adapted to lock the cross bar when the posts are turned to another position, locking means for said posts adapted 85
 45 to be engaged and disengaged by said rotative movement thereof, and saw guides mounted on said posts.
8. In a miter box, the combination of a base, a saw guide bar pivoted on said base and having saw guide post sockets therein, saw guide posts arranged in said sockets to be rotated therein, said posts being provided with cross bar engaging lugs at their upper ends, said posts being notched below said bar, spring post retainers mounted on said bar to engage said notches in said posts when the posts are adjusted to position, a cross bar having slots adapted to receive said lugs on said post when the posts are turned to one position, the lugs being adapted to lock the cross bar when the posts are turned to another position, locking means for said posts adapted to be engaged and disengaged by said rotative movement thereof, and saw guides mounted on said posts.
9. In a miter box, the combination of a base, a saw guide bar, a pivot for said bar carried by said base, said pivot being notched below said bar, a slotted locking slide mounted on said bar to be adjusted into engagement with the notches of said pivot whereby 65
 50 said bar is detachably retained thereon, saw guide posts removably mounted on said bar, and saw guides slidably mounted on said posts.
10. In a miter box, the combination of a base, a saw guide bar pivotally mounted thereon and having post sockets therein, posts arranged in said socket to be rotated therein and provided with cross bar engaging lugs at their upper ends, a cross bar having slots adapted to receive said lugs on said post when the posts are turned to one position, the lugs being adapted to lock the cross bar when the posts are turned to another position, locking means for said posts adapted 70
 55 to be engaged and disengaged by said rotative movement thereof, and saw guides mounted on said posts.
11. In a miter box, the combination of a base provided with back supports, back 85
 60 members disposed on said base against said supports, and a clamping screw disposed horizontally opposite to said back supports and spaced therefrom whereby a bar may be disposed between said back members and 90
 65 said clamping screw and clamped against said back members to hold them in position, said bar constituting a bed piece and a support for the miter box.

In witness whereof, I have hereunto set 95
 my hand and seal in the presence of two witnesses.

WELLINGTON D'ARCY. [L. S.]
